(57) **CLAIM**

The ornamental design for the set of game piece base and cube as shown and described.

DESCRIPTION

FIG. 1 is a left side, top, and rear perspective view of a base of the set of game piece base and cube, in accordance with the present invention;

FIG. 2 is a rear elevational view of the base of the set of game piece base and cube attached to a bottom of a chess piece;

FIG. 3 is a front elevational view of the base of the set of game piece base and cube attached to a bottom of a chess piece;

FIG. 4 is a left side elevational view of the base of the set of game piece base and cube attached to a bottom of a chess piece;

FIG. 5 is a right side elevational view of the base of the set of game piece base and cube attached to a bottom of a chess piece;

FIG. 6 is a top plan view of the base of the set of game piece base and cube;

FIG. 7 is a bottom plan view of the base of the set of game piece base and cube;

FIG. 8 is left side, top, and rear perspective view of the set of game piece base and cube, with the cube inserted into the base of the set of game piece base and cube;

FIG. 9 is a rear elevational view of the set of game piece base and cube, with the cube inserted into the base of the set of game piece base and cube;

FIG. 10 is left side, top, and rear perspective view of the set of game piece base and cube, with the cube shown separate from the base;

FIG. 11 is a rear elevational view of the set of game piece base and cube, with the cube shown separate from the base;

FIG. 12 is a left side, top, and rear perspective view of the base of the set of game piece base and cube, with a line 13-13 shown; and,

FIG. 13 is a cross sectional view of the base of the set of game piece base and cube, along the line 13-13 shown in FIG. 12.

(Continued)

The long dash-short dash broken lines in FIG. 12 is for the purpose of annotating the cross sectional line; all other long dash-short dash broken lines for the chess pieces depict environmental subject matter that forms no part of the claimed design.

1 Claim, 6 Drawing Sheets
